BACKGROUND OF THE INVENTION

In accordance with an embodiment of the present Invention relates to a modified suitcase incorporating a compartment from which would extend a lightweight telescopic cot. There is a suitcase with a built in collapsible cot structure in the back comprising a fabric Web, a frame, and folding legs. When set up, the cot structure provides for a person to lie down or sit on top of the fabric. There is a divider, where divider separates the luggage first compartment and cot in second compartment in one particular embodiment. The lugcot modification would ensure a place to set or sleep, was always available and the traveler did not have to rest upon the floor or ground. Not only will present invention benefit traveler, it will benefit camper for backpacks, military backpacks, forest fire fighter's backpacks.

The present suitcases only provide the service of carrying clothing and cosmetics. This Invention would carry clothing, cosmetics and bed.

BRIEF SUMMARY OF THE INVENTION

The Invention a modified suitcase would incorporate a compartment from which would extend a lightweight Cot. The design of his article of luggage would ensure the individual luggage was always attended as the cot would be secured to the base of the luggage. Thus, it would eliminate the luggage from being stolen. In this sense, this invention would provide travelers with enhanced safety and peace of mind.

**DETAILED DESCRIPTION OF THE
INVENTION**

10 The present invention relates to a travel luggage with a telescopic Cot extendable therefrom. The present invention provides travel Luggage that includes two compartments. One compartment is provided for the placement of clothing, toiletries and other travel accessories and a second compartment is provided where a telescopic Cot is stored. The present invention allows for the extension of a Telescopic Cot from the back of the Luggage. This Luggage along with Cot provides a means for a Traveler to create a bed to relax 15 during an extended lay-over at an airport, or on a hiking or camping trip, when visiting relatives, for military backpacks when wrist is needed and for forest fire fighters.

In reference to FIG. 1A, a perspective view of a Travel Luggage 6 views is depicted. The travel luggage includes a Main Body 3, with a First Side 2. As shown in FIG. 1, the back view Side 1, the back angle view 4, opens and allows the extension of a Cot 5, for use by the owner. The Cot 5, extends from a Compartment 1, as shown in FIG. 1 of the Luggage 4. In addition to the First first 1, the Luggage 1 also includes a Second Compartment also shown in FIG. 1. When in a closed position the Luggage 1 is similar to any other respective travel luggage that is used on the market. Travel Luggage 1 according to the present invention includes two compartments, one for storing clothing and other travel accessories in Second Compartment 7 and the First Compartment 6 for the storage of an Cot.

In reference to FIG. 1B, a perspective view of a Travel Luggage, 8 views is depicted, 1Locking Pin and Cot and frame of Cot. FIG. 1B a Perspective view shows the Cot being set up in a matter of minutes.

40 In reference to FIG. 1C a perspective view of a Travel Luggage, view 8, Locking Pin.

The invention claimed is:

1. A travel luggage, comprising:
a main body having a height, width, and a depth wherein
the main body defines a first compartment;
a handle extending substantially along the height of the
main body and attached to the back side of the main
body;
a second compartment, attached to the back side of the
main body and having a similar height and width as the
main body, that encloses the handle and includes a
pivotally attached door that is attached near the bottom
of the main body; and
a cot frame pivotally attached to the bottom of the end of
the handle that is contained within the second compartment
wherein the cot frame has a covering.
2. The travel luggage in claim 1, wherein the cot frame
includes a telescoped portion to enlarge the cot.
3. The travel luggage in claim 1, further comprising a
plurality of legs attached to the cot frame to support the cot.
